CLAIM

I claim the ornamental design for a toilet, as shown and described.

DESCRIPTION

FIG. 1 is a left side perspective view of a toilet in accordance with the present invention;

FIG. 2 is a front elevational view of the toilet in accordance with the present invention;

FIG. 3 is a rear elevational view of the toilet in accordance with the present invention;

FIG. 4 is a left side elevational view of the toilet in accordance with the present invention, the right side elevational view being the mirror image thereof; and

FIG. 5 is a top elevational view of the toilet in accordance with the present invention; and,

FIG. 6 is a bottom elevational view of the toilet in accordance with the present invention.

The broken lines shown in the drawing are included for the purpose of illustrating a portion of the toilet that forms no part of the claimed design.
